UNITED STATES PATENT OFFICE.

SAMPSON W. MOON, OF CHICAGO, ILLINOIS, ASSIGNOR TO HORTO ELECTRIC COMPANY, OF CHICAGO, ILLINOIS.

ELECTRIC MASSAGE AND VIBRATOR MACHINE.

No. 821,180.

Specification of Letters Patent.

Patented May 22, 1906.

Application filed May 18, 1905. Serial No. 280,980.

To all whom it may concern:

Be it known that I, SAMPSON W. MOON, a citizen of the United States, residing at Chicago, in the county of Cook and State of Illinois, have invented certain new and useful Improvements in Electric Massage and Vibrator Machines; and I do declare the following to be a full, clear, and exact description of the invention, such as will enable others skilled in the art to which it appertains to make and use the same.

This invention relates to improvements in electric massage and vibrator machines.

The object of the invention is to provide a machine of this character which is adapted for use in massaging the face, head, and body and for use by physicians in vibratory treatment and which may also be used in its larger or heavier forms for rubbing down and polishing all kinds of woodwork, furniture, &c., that are given a rubbed or polished finish.

Another object is to provide a massage and vibrator machine operated by electromagnets, the armature of which forms the vibrator-arm, said armature being pivotally mounted and evenly balanced by springs.

Another object is to provide means for regulating the speed and length of the vibrations, means being also provided for preventing the armature from striking the poles of the magnet, thereby making the machine practically noiseless.

With these and other objects in view the invention consists of certain novel features of construction, combination, and arrangement of parts, as will be hereinafter described and claimed.

In the accompanying drawings, Figure 1 is a perspective view of the device, showing 40 the same attached to the socket of an electric-light-circuit wire. Fig. 2 is a top plan view of the device with the upper half of the casing removed, showing the construction and arrangement of the vibrator mechanism. Fig. 3 is a detail horizontal sectional view through the adjusting-screws for regulating the speed and length of the vibrations of the armature. Fig. 4 is a detail sectional view through the outer end of the armature 45 or vibrator-arm and the massage-tool, and Fig. 5 is a similar view through the cushion device for preventing the armature from striking the poles of the magnet.

Referring more particularly to the drawings, 1 denotes the machine, which is here 55 shown as consisting of a substantially oval-shaped casing 2, formed in two parts, the upper part of which is removably secured to the lower in any suitable manner. To the lower part of the casing is secured a hollow handle 3. 60

Within the casing 2 is secured a supporting plate or frame 4, on which is mounted an electromagnet 5. Pivotal mounted on the frame or plate 4 is an armature 5', the outer end of which is bent at right angles to form a 65 vibrator-arm 6. On the outer side of the armature 5', near the pivoted inner end of the same, is secured a contact-spring 7, which is adapted to engage an adjustable contact-point 8. 70

Adapted to bear against the outer end of the armature adjacent to the inner end of the vibrator-arm is an expansion or push spring 9, the opposite end of which is connected with an adjusting-screw 10, whereby the tension of the spring is regulated. Connected to the armature on the opposite side of the magnet or near the pivotal connection of the armature is a retractile spring 12, the opposite end of which is connected to an adjusting-screw 13, by which the tension of the spring is regulated. These springs are provided for the purpose of balancing the armature and also for the purpose of forcing the armature away from the magnet when the latter is demagnetized. 75 80 85

As the force of the armature when so separated would be thrown against the contact-spring 7, the latter spring would soon become useless unless the force of the armature when moved by the spring 9 was checked. In order to check or relieve the force of the armature, the retractile spring 12 is provided. These springs when properly adjusted will evenly balance the armature. 90 95

In order that the armature will be prevented from striking against the poles of the magnet, and thus creating a noise, a bumper or cushion is provided against which the armature vibrates. Said bumper preferably consists of a hollow or tubular screw 13', adapted to be screwed through a threaded aperture in a lug 14, formed on the plate or frame 4. The screw 13' is held in its adjusted position in said lug by means of a set-screw 15. In the 100 105 hollow or tubular screw 13' is arranged an

elastic cushion, which is preferably and is here shown as a rubber plug 14', but which may be a coiled spring or any suitable form of cushioning device.

The contact-point 8 for the contact-spring 7 is formed on the inner end of an adjusting-screw 16, adapted to be screwed through an apertured lug 17, secured to the frame or plate 4. The outer end of the screw is provided with a knob 18, formed of non-conducting material, whereby the screw is adjusted in the lug 17 to bring the contact-point 8 into more or less close engagement with the contact-spring 7, thereby varying the speed and length of the vibrations of the armature or vibrator-arm. In order that the screw 16 will be held in its adjusted positions without the use of jam-nuts, a coiled spring 19 is arranged thereon between the inner end of the knob 18 and the lug 17, the tension of the spring holding the screw against casual movement.

On the knob 18 is secured a pointer 20, which when the knob and screw 16 are turned will move over a scale marked on the casing 2 and arranged to indicate the speed of the armature and the position of the contact-point 8 against the spring 7.

Connected with the magnet and the contact spring and point in the proper manner are the terminals of the conductor-wires 21 of the circuit, the opposite ends of which are here shown as connected to a condenser 22 of any suitable form and here shown as inclosed in an ornamental casing. The condenser is here shown connected by short conducting-wires 23 with a plug 24, adapted to be engaged with the socket of an electric-light-circuit wire. The conductor-wires 21 and 23 are insulated and inclosed in a suitable covering to form a flexible cord. By arranging the condenser in the conducting-wires or cord to be suspended thereby close to the point of attaching said conductor to the socket of the circuit-wires the condenser will be supported in an out-of-the-way position.

On the end of the vibrating arm may be secured any suitable form of massaging-tool 25, said tool being here shown as cup or bell shaped and formed of rubber.

A massage-machine constructed as herein shown and described will be found to be simple, strong, durable, and comparatively inexpensive in construction, efficient in operation, light in weight, and convenient and easily handled.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

1. In a massaging-machine, the combination with a casing having a handle, of an electromagnet arranged in said casing, a pivotally-mounted armature vibrated by said magnet, a vibrating tool-carrying arm arranged on said armature, a massage-cup secured to said arm, means whereby said armature is balanced when in its inoperative position, and means whereby the speed and length of the vibrations of the same are controlled and indicated substantially as described. 70

2. In a massaging-machine, the combination with a casing having a handle, of an electromagnet arranged in said casing, a pivotally-mounted armature vibrated by said magnet, a vibrating tool-carrying arm arranged on said armature, means whereby 85 said armature is balanced, a massage-cup secured to said arm, a spring-seated operating-knob whereby the speed and length of the vibrations of the same are controlled, and means whereby the armature is prevented 90 from striking the poles of the magnet when vibrating, substantially as described.

3. In a massaging-machine, the combination with a casing having a handle, of an electromagnet arranged in said casing, a pivotally-mounted armature vibrated by said magnet, a vibrating tool-carrying arm arranged on said armature, a flexible massage-cup secured to said arm, springs connected to said armature to balance the same when the electromagnets are demagnetized, a contact-spring fixed on said armature, an adjustable contact-point to coact with said spring whereby the vibrations of the armature are controlled and indicated, and means whereby the armature is prevented from striking the poles of the magnet, substantially as described. 100 105

4. In a massaging-machine, the combination, with a casing having a handle, of an electromagnet arranged in said casing, a pivotally-mounted armature vibrated by said magnet, a vibrating tool-carrying arm arranged on said armature, springs connected to said armature to balance the same in its 115 movements, a contact-spring fixed on said armature, an adjustably-mounted screw having on its end a contact-point to coact with said spring, whereby the vibrations of the armature are controlled, an operating-knob secured to said screw, a spring arranged on said screw to hold the same in its adjusted positions, and an indicating-pointer arranged on said knob to coact with a scale on said casing, substantially as and for the purpose described. 120 125

5. In a massaging-machine, the combination with a casing having a handle, of an electromagnet arranged in said casing, a pivotally-mounted armature vibrated by said 130

magnet, a vibrating tool-carrying arm arranged on said armature and a cushioned bumper to prevent said armature from striking the poles of said magnet said cushioned bumper comprising a rubber plug seated in a tubular screw, substantially as described.

6. In a massaging-machine, the combination with a casing having a handle, of an electromagnet arranged in said casing, a pivotally-mounted armature vibrated by said magnet, a vibrating tool-carrying arm arranged on said armature, and an adjustable cushioned bumper to prevent said armature from striking the poles of the magnets, said cushion-bumper comprising a rubber plug, a tubular screw seated in a lug and adjustable toward and from the armature substantially as described.

7. In a massaging-machine, the combination with a casing having a handle of an electromagnet arranged in said casing, a pivotally-mounted armature vibrated by said magnet, a vibrating tool-carrying arm arranged on said armature, springs connected to said armature to balance the same in its movements, a contact-spring fixed on said armature an adjustably-mounted screw having on its end a contact-point to coact with said spring, whereby the vibrations of the armature are controlled, an operating-knob secured to said screw, a spring arranged on said

screw to hold the same in its adjusted positions, an adjustable cushioned bumper to prevent said armature from striking the poles of the magnet and a massage-tool removably secured to said vibrator-arm substantially as described.

8. In a massaging-machine the combination with a casing having a handle, of an electromagnet arranged in said casing, a pivotally-mounted armature vibrated by said magnet, a vibrating tool-carrying arm arranged on said armature, springs connected to said armature to balance the same in its movements, a contact-spring fixed on said armature, an adjustable contact-point to coact with said spring whereby the vibrations of the armature are controlled, means whereby said armature is prevented from engaging the poles of the magnet, conducting-wires connected with said magnet and armature, a condenser connected with said conductor-wires, and a plug connected to said condenser to attach the same to the socket of an electric circuit, substantially as described. 55

In testimony whereof I have hereunto set my hand in presence of two subscribing witnesses.
